(57) **CLAIM**

The ornamental design for a slip electrical conduit coupler body, as shown and described.

DESCRIPTION

FIG. 1 is a front perspective view of a slip electrical conduit coupler body showing my new design.

FIG. 2 is a top view thereof.

FIG. 3 is a right side view thereof, the left side view being a mirror image thereof.

FIG. 4 is a bottom view thereof.

FIG. 5 is a front view thereof, the rear view being the same as the front view.

FIG. 6 is a front perspective view thereof in environmental use.

The broken lines in the drawings illustrate environment that form no part of the claimed design.
